CAM-ACTING GARMENT HANGER

Alvin W. Guthrie, Chicago, Ill.

Application December 27, 1946, Serial No. 718,856

3 Claims. (Cl. 223—89)

1

This invention relates to garment hangers, and in particular, a garment hanger having the usual coat-supporting element with cam-gripping elements for suspending skirts, trousers and the like in tension below a lower horizontal bar of the hanger.

The use of the common form of garment hanger with a centrally disposed hook is being extended universally to include supporting means for various types of garments, and it is difficult to support garments such as short skirts and children's trousers from the usual horizontal bar of a hanger. To accomplish this end, the garment hanger of this invention includes gripping jaws associated with supporting pins and cams, wherein in the jaws may be slid outward in gripping relation with the garment and which, when so positioned, will remain in the gripping position holding the garment in tension and suspending it from the horizontal bar of the hanger.

The purpose of this invention is, therefore, to provide an improved garment hanger wherein gripping jaws are slidably mounted in a lower horizontal bar thereof and designed so that their inner ends form cams that coat with an inner surface of the bar to lock the jaws in substantially any position to which they are moved.

Garment hangers have been provided in which the width thereof is adjustable, and others have been provided with resiliently mounted skirt and trousers-supporting elements, but these are comparatively complicated, and the cost of manufacturing thereof is prohibitive.

The object of this invention is to provide gripping elements for skirts, trousers and the like in combination with garment hangers wherein all resilient elements and substantially all moving parts are eliminated.

Another object is to provide a garment hanger having garment-gripping jaws slidably mounted in the lower horizontal bar thereof wherein the tension of the garment supported by the jaws locks the jaws in substantially any position to which they are moved.

Another object is to provide means for mounting gripping jaws in a horizontal member of a garment hanger wherein the jaws are readily adjustable to grip garments of different sizes.

Another object of the invention is to provide gripping jaws in a horizontal member of a garment hanger wherein the jaws may be adjusted to suspend garments in tension so that creases and the like will remain in the garments.

Another object is to provide gripping elements in combination with a garment hanger wherein

comparatively short garments may be positively suspended and held to the hanger until manually released.

A further object is to provide a garment hanger having slideable cam-acting gripping jaws in a lower horizontal member thereof which is of a simple and economical construction.

With these and other objects in view, the invention embodies a garment hanger having a centrally disposed hook with downwardly sloping depending arms, a horizontal bar suspended from the ends of the arms, and gripping jaws with cam-shaped inner ends slidably and pivotally mounted in said horizontal bar.

15 Other features and advantages of the invention will appear from the following description taken in connection with the drawings wherein:

Figure 1 is a view showing a side elevation of the garment hanger with the gripping jaws extending downward from a horizontal bar thereof.

20 Figure 2 is a cross-section through the horizontal bar of the hanger on line 2—2 of Figure 1, showing one of the gripping jaws mounted in slots therein and with the upper portion of the hanger broken away.

25 Figure 3 is a longitudinal section through one end of the garment hanger with parts broken away.

Referring now to the drawings, wherein like reference characters indicate corresponding parts, the garment hanger of this invention includes a horizontal bar 10 which is suspended in the ends of depending arms 11 and 12 of a hanger element with a centrally disposed hook 13 associated with the upper ends of the depending arms.

30 The ends of the horizontal bar 10 are mounted on the ends of the depending arms 11 and 12 by supporting elements 14 and 15, as illustrated in Figure 3, or the elements may be attached in any manner or by any means.

35 The horizontal bar 10 may be made of wood, plastic, metal or any suitable material, and it is preferably of U shape in cross-section, as illustrated in Figure 2. Centrally disposed in the bar is a continuous longitudinal slot 16 with comparatively small side grooves 17 and 18 in which the extending ends of a pin 19 extending through a jaw 20 are slidably held.

40 The jaws 20 may be of any shape or design. However, in the design shown they are formed with tapering outer ends having knurled or roughened gripping surfaces 21 on their outer faces, and their inner ends are shaped as shown in Figure 3 with arcuate cam-shaped surfaces 22

positioned to contact an upper inner surface 23 at the end of the slot 16. With the inner ends of the jaws shaped in this manner, a garment held against the knurled surface 21 will urge the jaws to substantially vertical position, and the cam surfaces 22 will bind against the surface 23 with toggle or wedge action, thereby positively holding the jaws in substantially any position along the bar. It is only necessary, therefore, to place one side of the waistband of a skirt on one of the jaws and then move the other jaw outward to gripping relation with the upper side of the waistband, and then the jaw may be released as the cam surfaces will positively hold both jaws in gripping relation with the skirt.

The cam-acting garment hanger of this invention, therefore, includes the elements of a usual garment hanger including a hook with depending downwardly sloping arms and a horizontal bar suspended in the ends of the arms, and as an improvement over the usual garment hanger, gripping jaws pivotally and slidably mounted in said horizontal bar and extending downward from the under surface thereof where they may readily be positioned for gripping action with skirts, trousers or other garments and the tension of the garment provides the holding or locking means that holds the jaws in gripping relation with the garments.

The improved garment hanger of this invention is illustrated in its preferred form. However, it will be understood that modifications in the design and structural elements may be made without departing from the spirit of the invention.

What is claimed is:

1. In a garment hanger having a hook with depending arms and a horizontal bar suspended from the ends of the arms, gripping jaws with cam-shaped inner ends and knurled surfaces on their outer ends slidably mounted in a longitudinally extending slot in the horizontal bar, said jaws having pins on the sides extending

into grooves in the sides of the slot said cam-shaped inner ends being adapted, when rotated on said pins, to bind against the top of the slot for holding the jaws in selected positions, and said knurled surfaces being adapted to resist slipping of garments disposed thereagainst.

2. A garment hanger comprising a bar formed with a longitudinally-extending slot having opposed longitudinally-extending grooves on the inner surface thereof, and a pair of gripping jaws with cam-shaped inner ends disposed in said slot and provided with pivot pins extending into said grooves, said jaws being adapted to be moved slidably on their pins along said grooves to selected positions, and said cam-shaped inner ends being adapted, when rotated on said pins, to bind against the top of the slot for holding the jaws in selected positions.

3. A garment hanger comprising a bar formed with a longitudinally-extending slot having opposed longitudinally-extending grooves on the inner surface thereof, and a pair of divergently-positioned gripping jaws with cam-shaped inner ends disposed in said slot and provided with pivot pins extending into said grooves, said jaws being adapted to be moved slidably on their pins along said grooves to selected positions, and said cam-shaped inner ends being adapted, when rotated on said pins, to bind against the top of the slot for holding the jaws in selected positions.
